UNITED STATES PATENT OFFICE

CALEB K. COLBY, OF BROOKLYN, NEW YORK.

WATCH-PENDANT.

SPECIFICATION forming part of Letters Patent No. 287,001, dated October 23, 1883.

Application filed February 1, 1883. (No model.)

To all whom it may concern:

Be it known that I, CALEB K. COLBY, a citizen of the United States, and a resident of Brooklyn, Kings county, New York, have invented certain Improvements in Watch-Pendants, of which the following is a specification.

My invention relates to a stem-winding pendant for watches, being especially adapted to that class of watches wherein the back of the case is permanently closed and the movement, or the ring in which it is mounted, is hinged to the cup-like case. My pendant may, however, be used in any watch-case.

In watches having stem-winding pendants the key in the pendant passes into the movement and engages a socket or square in or on the winding-arbor, and before the movement can be lifted out or turned on its hinge this key must be disengaged from the movement by withdrawing it far enough to clear the latter. My invention provides a ready means for doing this, which I will now describe with reference to the accompanying drawings, where-

in—
25 Figure 1 is a vertical mid-section of a watch-pendant provided with my improvements, the plane of the section being taken edgewise of the watch-case, and the key shown as protruding into the hollow of the winding-arbor. Fig. 30 2 is a similar section taken at right angles to Fig. 1, showing the key withdrawn, so as to permit the movement to be lifted out. Fig. 3 is a detached sectional view of the key and its attachments, and Fig. 4 is an end or bottom 35 view of the same. Figs. 5, 6, 7, 8, 9, 10, 11, 12, and 13 illustrate modifications which will be referred to more particularly hereinafter.

Let A represent a watch-case, of a cup form, of which I have shown only the portion adjacent to the pendant. B is the tubular stem, attached to the case in the usual way. C is the key, and D is the crown attached thereto to form a head or thumb-piece, by which the key is turned in winding. These parts, *per se*, are common in stem winding and setting watches. Figs. 1 to 4 show the preferred construction.

In the inside wall of the tubular stem B, I form two internal circular grooves, a and a', 50 at different depths in the hollow of the stem,

as shown, to form latch-bearings for the rotating key, and to the crown D or the key C, indifferently, I secure a latch spring or springs, b b, preferably four, provided with projecting angles or parts b', to spring into and engage 55 one or the other of grooves a a' when the said springs are inserted in the hollow of the stem, as fully illustrated in Figs. 1 and 2. When the key, with the crown and springs attached, (see Fig. 3,) is inserted in the hollow of the 60 stem and pressed down, as in Fig. 1, the elasticity of the springs causes the projections b' thereon to engage the lower groove, a. The key will now be in engagement with the winding-arbor C in the movement F, (if there be a 65 movement in the case,) and by rotating the key in the usual way the watch will be wound up. The bearing which the key finds in the neck of the stem and that which the crown finds on the exterior surface of the stem prevent any lateral play of the key, and the engagement of the latch-springs b in groove a 70 prevents any longitudinal movement of the key, unless some force is applied to move it. In other words, the key rotates readily, but 75 only yields to extra pressure purposely exerted when an attempt is made to withdraw it longitudinally. If, however, it be desired to disengage the key from the movement for any purpose whatever, the operator may grasp the 80 crown and pull on it with force sufficient to disengage the springs from groove a, when the key may be withdrawn far enough for the projection b' to engage groove a'. The parts will now assume the position shown in Fig. 2, 85 the key will be withdrawn far enough to be free from the movement, and it may be rotated freely in this position in the bearing found in the groove a'.

I prefer to construct my pendant as represented in Figs. 1, 2, 3, and 4—that is to say, to secure the springs to the crown by means of a shoulder on the key, which has a screw on its end to screw into the crown; but these parts may as well be secured together in any 95 way desired—as, for example, they may be brazed or soldered together.

In lieu of forming both grooves a and a' with inclined faces, and the projections b' on the springs with inclined faces to fit them, I 100

may make the upper or outer face of groove *a* with a perpendicular face, as shown in Fig. 5, and make the face of the projection *b* to fit it. In this construction the key could not be 5 readily withdrawn entirely from the stem should the effort to withdraw or shift it be too energetic, as the square shoulder of the groove *a* would serve as a stop or detent.

In lieu of employing the two grooves *a* *a'* 10 in the stem and one series of projections *b*' on the springs, I may employ but one groove *a*, as in Fig. 6, and provide the springs with two series of projections *b*'.

In Fig. 7 I have shown a further modification, in which the springs are mounted in the hollow of the stem, and the two series of projections *b*' thereon protrude through slots in the wall of the stem. A groove in the margin of the opening in the hollow crown *D* takes 15 over and engages the lower one of these projections, as clearly shown in said figure.

In Figs. 8 and 9 I have shown a further modification of this last-described device, in which the springs in the stem have but one series of 20 projections *b*', and the exterior surface of the stem is or may be provided with rigid stops *c*, to prevent the key from being entirely withdrawn. Fig. 8 shows an end view and a perspective view of the stem so provided, and 25 Fig. 9 shows a view of the under side of the crown provided with recesses *d* in the margin of the aperture in its base. When the recesses *d* are brought to coincide or register with the stops *c*, the crown may be slipped on or off. 30 These stops may or may not be placed in line with the projections *b*'.

In Fig. 10 I have shown the grooves *a* and *a'* 35 formed in the shank of the key itself and the latch-springs mounted in the stem, and in Fig. 40 11 I have shown the same arrangement, except that the key is provided with projecting ribs *b*', and the springs have recesses *a* to engage said ribs.

In Fig. 12 I have shown the grooves *a* *a'* 45 arranged exteriorly of the stem and the springs arranged to engage them in that position.

In Fig. 13 I have shown the same arrangement as in Fig. 1; except that the free ends of the springs are arranged to rest on a collet, *e*, 50 formed on the shank of the key.

I have shown all of these forms and modifications in order to illustrate the many ways in which my invention may be carried out. The essential features of all is the elastic or spring 55 latch attachment of the stem *B* with the key *C*, whereby the latter is free to rotate, but is prevented from being moved longitudinally, except by a special effort. The annular groove or rib engaged by the spring-latch I denominate an "annular latch device," and it is immaterial whether the projecting part is on the spring or the other part, and it is also immaterial whether the spring be connected with the key or the tubular stem. The operation is the 65 same in either case.

The upper groove, *a'*, in the stem is not ab-

solutely necessary, as it is not necessary that the key shall be rotative when drawn back, as in Fig. 2; but some form of stop should be provided to prevent the key from being entirely withdrawn. This withdrawal of the key is not desirable, although it will do no particular harm. Figs. 5, 7, 8, and 9 show stops which will effectually prevent the key from being fully withdrawn by inadvertence. 70

The crown *D* may be considered as a part of key *C*, or a provision thereon. From this point of view the groove *a* in Fig. 7 may be considered as in the key or moving part of the pendant, instead of in the stem or non-moving part, as in Fig. 1. 75

E is the ordinary suspension-ring of the pendant.

I have not shown how my key *C* may be employed as a push-pin for releasing the lid 85 of the case from its spring-catch, as I make no claim to this. I will say, however, that the tip of the key passes through the case-spring, and a shoulder on its shank rests on the latter. The retaining-groove *a* is made wide enough 90 to allow of the necessary slight movement longitudinally of the key. This is a common mode of constructing such push-pin devices.

It must be borne in mind that my invention is designed to be applied only to the pendants 95 of stem-winding watches wherein the key is mounted rotatively in the stem and projects normally into the movement to engage the winding-arbor.

I am aware that it has been proposed to 100 provide "key-winding watches," so called, with a chambered stem, and to insert the key into this stem simply as a retaining-pocket, wherein it is held by a spring to prevent it from dropping out. In this construction, however, the 105 key does not project into the hollow of the case, nor is it desirable or necessary that the chamber in the stem shall connect with the hollow cavity of the case, except incidentally to provide room. Keys mounted in pockets 110 in the stems in this manner do not or need not rotate. In the stem-winding pendant herein shown the key must project into the case and must rotate, and it is not intended that it shall ever be withdrawn from the hollow of the stem or be detached from the case. 115

Having thus described my invention, I claim—

1. The combination, in a stem-winding watch, of the tubular stem, a key mounted to 120 rotate in said stem and to project into the movement and engage the winding-arbor, as shown, a spring attached to one of these parts and arranged to engage the other part to form a latch device, as shown, and the said winding-arbor, all arranged substantially as and for the purposes set forth.

2. The combination, in a stem-winding watch, of the case *A*, the tubular stem *B*, provided with a groove, *a*, or its specified equivalent, the key *C*, the movement provided with a winding-arbor, *e*, arranged opposite to the key 130

C and adapted to be engaged thereby, and the spring *b*, attached to the key and arranged to engage the groove *a* in the stem, to form a latch device to keep the key in engagement with the arbor *c*, substantially as and for the purposes set forth.

3. The combination, to form a stem-winding pendant for a watch, of the tubular stem provided with two annular grooves or their specified equivalents, arranged at different depths therein, as set forth, a key mounted rotatively in said stem and arranged to engage the winding-arbor normally, said winding-arbor, and a spring, *b*, secured to the key, and provided with 15 an angular projection, or its specified equivalent, adapted to engage either of the annular grooves in the stem, to form an elastic retaining device whereby the key may be held in either

of two positions in the stem, substantially as set forth.

4. The combination, in a watch-pendant, of the tubular stem provided with a groove, *a*, and a stop-groove, *a'*, or its specified equivalent, the key, the crown, and the spring *b*, the said key, crown, and spring being secured together, and the spring being provided with projections *b'*, arranged to engage, elastically, the grooves in the stem, substantially as and for the purposes set forth.

In witness whereof I have hereunto signed 30 my name in the presence of two subscribing witnesses.

CALEB K. COLBY.
